INVENTOR.
LORN CAMPBELL JR.
BY HIS ATTORNEY.

James F. Williamson

UNITED STATES PATENT OFFICE.

LORN CAMPBELL, JR., OF MINNEAPOLIS, MINNESOTA, ASSIGNOR TO UNITED STATES WELDING COMPANY, OF MINNEAPOLIS, MINNESOTA, A CORPORATION OF MINNESOTA.

LIQUID-FUEL BURNER.

Application filed December 13, 1922. Serial No. 606,618.

To all whom it may concern:

Be it known that I, LORN CAMPBELL, Jr., a citizen of the United States, residing at Minneapolis, in the county of Hennepin and 5 State of Minnesota, have invented certain new and useful Improvements in Liquid-Fuel Burners; and I do hereby declare the following to be a full, clear, and exact description of the invention, such as will enable others skilled in the art to which it 10 appertains to make and use the same.

This invention relates to a burner and particularly to a burner designed to burn liquid fuel. The use of liquid fuel in furnaces, especially the furnaces of heating plants, is 15 greatly on the increase. Such burners are meeting with considerable favor owing to the elimination of ashes and reduced labor of handling the fuel. The burners heretofore used, however, have developed many 20 objectionable features, among which may be noted the necessity of frequent cleaning. If the burner comprises such parts permanently connected together and secured in a fire box, 25 this cleaning operation is very difficult.

It is an object of this invention to provide a burner of extremely simple and efficient construction which can be installed in an ordinary furnace with a minimum of trouble.

It is a further object of the invention to provide such a burner consisting of few parts, which parts are easily assembled and disassembled.

It is also an object of the invention to provide a burner having a novel and efficient vaporizing means and one which will not require frequent cleaning.

It is a still further object of the invention to provide a burner so arranged that it can be adjusted between wide limits as to the size of the flame and the amount of fuel consumed.

These and other objects and advantages of the invention will be fully set forth in the following description made in connection with the accompanying drawings in which like reference numerals refer to the same parts in the different views and in which,

Fig. 1 is a central vertical section through the burner; and

Fig. 2 is a similar view showing a burner of modified construction.

Referring to the drawings, the grate bars of an ordinary furnace are designated as 1. 65 The burner of the present invention is con-

structed so that it may be placed directly on said bars and said burner comprises a casing 2 illustrated as resting on the bars 1. The basing 2 is shown with an outwardly extending flange at its lower edge and in order to direct the air passing through the grate through the casing and to position the casing, a layer of fire clay 3, or some similar material is placed upon the bars and extends over the said flange. A dish-shaped plate 4 is supported in the casing 2 and in the embodiment of the invention illustrated, this plate is shown as supported by spaced lugs 5 projecting inwardly from the inner wall of the casing 2. Said casing is formed with a shouldered top edge and a ring 6 has its lower edge shouldered to fit on said top edge and this ring has its top portion extending inwardly to form an inturned flange. Supported upon the plate 4 is a vaporizing member comprising a hollow head 7 of flaring or inverted conical shape. This head 7, as shown in Fig. 1, has an opening through its lower portion and an outwardly extending upturned flange 8 projects from this opening, which flange, as will be noted, at its outer edge, is substantially parallel with the plate 4 and is spaced a short distance therefrom, being shown as supported on said plate by a plurality of spaced bosses or feet 9. The head 7 is formed with a downwardly sloping rib 13 on its inner wall forming a trough or groove, which rib is thus substantially helical. A fuel outlet pipe 10 extends upward through the bars 1 to the burner and is threaded in a hole extending through a central hub in the plate 4 and a continuation of this fuel conduit is shown as the pipe 11 which is threaded into the top side of the said aperture in the hub of the plate 4. An outlet pipe or conduit 12 also extends through the grate bars 1 and is threaded into a boss on the plate 4. It will be noted that there is another boss on the upper side of plate 4 coaxial with the pipe 12, which latter boss extends a short distance above the surface of said plate.

It will be noted that the inlet conduit 11 is bent so as to deliver the fuel into the trough of groove formed by the rib 13. When the burner is in operation, the head 7 will be heated and the liquid fuel dropping upon the heated inner wall thereof will be vaporized almost instantly. The said fuel if not at once vaporized will travel downward some-

what in the trough formed by the rib 13 and quickly will be vaporized. It is possible for the fuel to pass around the wall of the burner and it may thus be brought into contact with quite a large area of the inner wall of head 7. This vaporized fuel will pass through the central opening adjacent the bottom of the head 7 and will pass out between the flange 8 and the plate 4, there thus being a plurality of passages radially outward between said plate and between the bosses or legs 9. The lugs 9 are located adjacent the edge of plate 4 and the passages between said lugs thus terminate adjacent the edges of plate 4. The air will enter between the grate bars 1 and pass upward in the casing 2 between the inner wall thereof and the edge of the plate 4 and flange 8. This air will thus pass adjacent the ends of the passages through which the vaporized fuel issues and a combustible mixture will be formed which will pass upward around the edge of the ring 6. This mixture will be directed inwardly by said ring and will then pass up about the head 7. The mixture will be ignited immediately adjacent the edge of the plate 6 and the flame will thus play upon the exterior wall of the head 7, which head will be heated and vaporize the fuel delivered to the inner wall thereof, as already described. If, for any reason, more oil is delivered than is vaporized, the same will be collected on plate 4 and if the collection of oil thereon is of sufficient depth to overflow the lug at the top of pipe 12, said oil will pass downwardly through said pipe. This oil, if desired, may be used to regulate a shut-off valve for the pipe 10 in a manner now well known in the art. It will, of course, be apparent that the top of the boss above pipe 12 is in a lower plane than the edge of the plate 4 so that no oil can collect in the plate 4 and run over the edge thereof. The top of the head 7 is substantially flat, although the same is shown with a slight dished construction in order to more easily allow for expansion of the burner due to the heating thereof.

In the modification shown in Fig. 2, the casing 2^a is used similar to the casing 2 and having a ring 6^a at the top thereof. A plate 14 is supported in the casing 2^a on lugs 5^a. The head 15 is flared or of mushroom shape substantially the same as the head 7 and the top of the head 15 is substantially horizontal although formed with a series of waves or corrugations designed to permit more ready expansion of the head when heated. The head 15 is provided with a rib 13^a similar to the rib 13 in Fig. 1. This head 15 has a central opening at its lower side which is shouldered to fit over the shouldered edge of a member 16. This member 16 is illustrated as an open ended cylinder having projections or legs 17 adapted to

rest upon the plate 14. Said member 16 has an imperforate bottom adjacent which are arranged a plurality of holes extending radially through the wall thereof and into which are threaded or otherwise secured, a plurality of pipes 18 inclined slightly downwardly and having their outer ends adjacent the edge of the plate 14. A fuel inlet conduit is provided comprising the pipes 10^a and 11^a threaded into a central hub on the plate 14, the pipe 11^a being bent slightly on its upper end to deliver into the groove or trough formed on rib 13^a. An outlet pipe 12^a is also provided extending through the grate bars 1^a and threaded into the plate 14 and a hub is formed on the upper side of said plate co-axial with the pipe 12^a. The plate 14 is also provided with a plurality of circumferentially arranged apertures 19, each surrounded by an up-raised flange at the upper side of said plate and a plate 20 is disposed under the plate 14 in contact therewith carrying a hub rotatable on the pipe 10^a. This plate 20 is also provided with a plurality of circumferentially arranged holes adapted in one position to align with the holes 14. When the plate 20 is rotated, however, the holes therein will be moved out of alignment with the holes 14 and the latter holes closed or partially closed by said plate. The plate 20 will also be provided with a short arcuate groove to accommodate the pipe 12^a. Said plate can be turned by arm 22 secured to sleeve 21 on said plate, the sleeve 21 being supported on collar 23.

In operation, the fuel will be delivered under pressure or by gravity to the inlet conduits 10^a and 11^a and will be delivered to the inner wall of the head 15 in the groove formed by the rib 13^a. As the head 15 is heated this fuel will be vaporized, as above described. The vaporized fuel will pass to the lower part of the head 15 into the portion 16 thereof and will issue through the pipes 18. The air entering between the grate bars will pass upward through the casing 2^a and through the opening between the edge of plate 14 and said casing. It will there be mixed with the vaporized fuel and the mixture will be directed inwardly by the member 6^a and will rise about the head 15. The mixture will be ignited adjacent the edge of the member 6^a and the flame formed will play about the head 15 and heat the same. With this structure of burner, the supply of fuel can be turned very low and small flames will burn adjacent the ends of the pipes 18. If any fuel should pass to the lower portion of head 15 and out through the pipes 18, the same would be ignited and burn in the plate 14, thus assisting in the vaporization. When the burner is regulated so that there is a small flame burning at the ends of the pipes 18, the plate 20 may be turned to admit air through the apertures 19.

14. This air will more readily mix with the vapor issuing from the pipes 18 and insure that said vapor will be supplied with sufficient air to keep the flame burning.

5 If the flame should be extinguished and oil continue to flow so that the same is collected in the plate 14 in considerable quantities, this oil will flow out through the pipe 12^a, which pipe may have connected thereto a suitable shut-off mechanism such as now well known in the art. It will, of course, be understood that the pipes 10 and 10^a will be provided with suitable regulating valves 24 and 24^a, respectively, which 10 may be either manually or automatically controlled. When the burner is first started, the head 7 or 15 may be heated with a bunch of waste soaked in oil or torch such as now 15 commonly used with oil burners.

20 From the above description it is seen that applicant has provided a very simple and efficient burner particularly adapted to be used in a heating furnace. The burner can be very easily, quickly and inexpensively installed in the standard type of furnace. It requires no special supporting means. The parts of the burner are furthermore, very few and of simple construction and the assembling of the burner in the furnace is a 25 very simple matter. Small pressure is required to feed the oil and the burner works very successfully with the storage tank but slightly higher than the ends of the pipes 11 or 11^a.

30 In practice, the liquid fuel is vaporized, as above stated, soon after it is deposited on the inner wall of the head 15 and rarely travels far in the groove therein before being completely vaporized. It will also be 35 obvious that the parts of the burner can be easily and quickly disassembled, if for any reason such operation becomes necessary.

40 It will, of course, be understood, that various changes may be made in the form, details, arrangement and proportions of the parts without departing from the scope of applicant's invention, which, generally stated, consists in the matter shown and described and set forth in the appended claims.

45 What is claimed is:

1. In a liquid fuel burner, the combination 50 of a vaporizing head having a radially lower extending flange, a dish supporting said head, said head having a plurality of fuel openings between the same and said dish, an air conducting casing surrounding and supporting said dish and forming an air opening between said dish and said casing and means for supplying fuel to said head.

55 2. The structure set forth in claim 1 and an inwardly deflecting ring above said first mentioned and last mentioned openings jointed to the top of said casing.

60 3. In a liquid fuel burner, the combina-

tion of a hollow vaporizing head having a radially extending flange on its lower end, a dish supporting said head, means forming a plurality of fuel openings between said dish and said head, an air inlet casing surrounding and supporting said dish and a fuel deflector ring jointed to the top of said casing, said ring deflecting the fuel onto the flange of the vaporizing head whereby a combustible mixture is formed and directed 70 upwardly to be burned about said head. 75

4. A liquid fuel burner comprising, a head having an upwardly flaring wall with a substantially horizontal top, said wall being reversely curved at its bottom portion and having said portion extending outwardly and forming a central opening into said head, a plate spaced from and extending substantially parallel to said bottom portion, said plate supporting said head, and means for delivering fuel upwardly through 80 said opening into said head. 85

5. The structure set forth in claim 4, and a casing opening at its upper end supporting said plate and surrounding said plate, and the bottom portion of said head adapted to direct a combustible mixture upwardly 90 around said head. 95

6. A liquid fuel burner comprising an upwardly flaring hollow head having an interior conical chamber, fuel receiving means on the inner wall of said head, fuel supplying means extending upwardly into said head and adapted to deliver to said fuel receiving means and a casing having an open 100 lower end through which air is adapted to pass surrounding the lower portion of said head and slightly spaced therefrom. 105

7. A liquid fuel burner comprising an upwardly flaring hollow head having an interior conical chamber, fuel receiving means on the inner wall of said head, fuel supplying means extending upwardly into said head and adapted to deliver to said fuel receiving means, outlet means for fuel vapor 110 at the lower end of said head, and means for directing air adjacent said outlet means and for directing the surrounding mixture upwardly to be burned around said head. 115

8. An oil burner having in combination an upper portion including an upwardly flaring hollow head, a fuel supply means extending upwardly into said head and adapted to deliver oil to the inner wall thereof 120 said head having a constricted zone at its lower end, a casing surrounding said portion adjacent its lower end and spaced slightly therefrom, said portion having a plurality of spaced passages communicating with said zone from said head leading toward said casing whereby air passing up through said casing will mix with the gas issuing from said passages to form a combustible mixture to burn about the flaring 125 wall of said head and heat the same. 130

9. An oil burner having in combination, an upper portion including an upwardly flaring hollow head having a constricted zone at its lower end, and a plate member 5 below said head, said portion having a plurality of passages communicating with said zone from said head and leading to adjacent the edge of said plate, said head having a fuel receiving means on its inner wall, a 10 fuel supply means extending into said head and delivering fuel to said last mentioned means, and a casing open at its bottom having a top inwardly directed flange surrounding and spaced slightly from the edge of 15 said plate.
10. An oil burner having in combination, an upper portion including an upwardly flaring hollow head having a constricted zone at its lower end and a dish-shaped plate therebeneath, a fuel supply means extending 20 upwardly into said head and adapted to deliver oil to the inner wall of said head, a casing surrounding said plate and lower part of said head having an upper inturned flange spaced slightly from the edge of said 25 plate, said first mentioned portion also including a plurality of passages communicating with said zone and leading to adjacent the edge of said plate, whereby air may rise in said casing and mix with vaporized fuel issuing from said passages.

In testimony whereof I affix my signature.

LORN CAMPBELL, JR.
